CLAIM

The ornamental design for a mixing manifold, as shown and described.

DESCRIPTION

FIG. 1 is a top perspective view of the mixing manifold showing my new design.

FIG. 2 is a bottom perspective view thereof.

FIG. 3 is a back view thereof.

FIG. 4 is a front view thereof.

FIG. 5 is a side view thereof.

FIG. 6 is another side view thereof.

FIG. 7 is a top view thereof; and,

FIG. 8 is a bottom view thereof.

The broken lines in the drawings illustrate portions of the mixing manifold which form no part of the claimed design.
